UNITED STATES PATENT OFFICE.

CYRUS CORL AND ALBERT P. PORR, OF ALTA, IOWA.

BELT-TIGHTENER.

SPECIFICATION forming part of Letters Patent No. 442,514, dated December 9, 1890.

Application filed September 20, 1890. Serial No. 365,647. (No model.)

To all whom it may concern:

Be it known that we, CYRUS CORL and ALBERT P. PORR, citizens of the United States, residing at Alta, in the county of Buena Vista 5 and State of Iowa, have invented certain new and useful Improvements in Belt-Tighteners; and we do hereby declare the following to be a full, clear, and exact description of the invention, such as will enable others skilled in 10 the art to which it appertains to make and use the same.

Our invention consists in a new and improved belt-tightener for tightening belts and holding them while their ends are being laced 15 or otherwise fastened together, our invention combining great simplicity of construction with effectiveness and convenience in use; and our invention will be hereinafter fully described and claimed.

Referring to the accompanying drawings, Figure 1 is a perspective view of our new and improved belt-tightener, showing the same arranged in its operative position with the ends of a belt between its clamps. Fig. 2 is 25 a similar view showing the hand-lever removed, and Fig. 3 illustrates in detail certain parts which will be hereinafter described.

The same letters of reference indicate corresponding parts in all the figures.

Referring to the several parts by letter, A A' indicate the end clamps of our tightener, between which the ends of the belt are secured. These clamps consist each of two flat parallel metal strips or bars a a', secured 35 together at their ends by screws b, on the ends of which nuts b' are screwed. The top bar a of the clamp A is formed with a central circular aperture a², while the top bar a' of the other clamp is formed with recessed bearing-lugs a³ in its inner upper edge.

B indicates a rack-bar having the series of inclined teeth B' on its upper edge and formed at one end with a downwardly-extending pivot-pin B², adapted to fit in the central 45 aperture a² of the clamp A.

C indicates a metal yoke, the free ends of which are formed with the rounded lugs c, and the yoke is formed on the under side of its center with a beveled detent C'.

In operation the ends of the belt are secured between the clamps A A', which may

be done by removing the screw at one end of each clamp and slipping the end of the belt into the clamp, when the screws are replaced and the nuts tightened to firmly clamp the 55 belt ends in the clamps. The pivot-pin B² at the end of the rack-bar B is then fitted in the central aperture a² of the clamp A, the free end of the bar resting on the clamp A', and the ends of the yoke C are engaged with the 60 recessed bearing-lugs a³ of the clamp A'. The end lever D is then placed in position on the rack-bar by fitting its bifurcated lower end d over the bar, and the hook E, which is pivoted to the lever, is caught in an eye C² on the 65 center of the yoke C. A metal clip F is then placed over the rack-bar, and is pivoted at its lower end to the lower end of the lever by an easily-removable pivot-pin G. The upper end of this clip is formed with a beveled detent 70 F', adapted to engage with the inclined teeth of the rack-bar. It will now be seen that on drawing back the handle of the lever the detent on the upper end of the clip F will engage with the teeth of the rack-bar, while the 75 lever will pull the yoke C over the top of the said bar, the detent C' of the yoke sliding over the inclined teeth and the two clamps A and A', and consequently the two ends of the belt being thus drawn toward each other. 80 When the lever-handle is pushed forward, the detent C' of the yoke C will engage with the teeth of the rack-bar, thus locking the yoke and holding the two clamps and the ends of the belt at the point to which they have been 85 stretched toward each other, while the lower end of the lever slides back, carrying the clip F over the rack-bar, so that on the next backward movement of the lever-handle the clamps will be drawn still closer together. When the 90 belt is stretched sufficiently tight, the pin G is pulled out, and the lever, with the clip F and the hook E, are removed out of the way, the yoke C, locked on the rack-bar, holding the ends of the belt firmly as they have been 95 stretched ready to be laced or otherwise fastened together.

The construction, operation, and advantages of our new and improved belt-tightener will be readily understood from the foregoing 100 description, taken in connection with the accompanying drawings. It will be seen that

our invention is very simple, strong, and durable in its construction and exceedingly effective and convenient in its operation.

Having thus described our invention, what we claim, and desire to secure by Letters Patent, is—

1. In a belt-tightener, the combination of the clamp A, having the bearing-aperture a^2 , the clamp A', having the recessed bearing-lugs a^3 , the rack-bar having the end pin B^2 , the yoke C, having the end lugs, the detent C', and the central eye C², the lever having the bifurcated lower end and the pivoted hook E, the clip F, having the detent F' at its upper end, and the removable pivot-pin G, substantially as set forth.
- 15 2. The combination of the clamp A, having

the bearing-aperture a^2 , the clamp A', having the recessed bearing-lugs a^3 , the rack-bar having the end pin B^2 , the yoke C, having the end lugs, the detent C', and the central eye C², the lever having the bifurcated lower end and the pivoted hook E, the clip F, having the detent F' at its upper end, and the removable pivot-pin G, substantially as set forth. 20

In testimony whereof we affix our signatures in presence of two witnesses.

CYRUS CORL.
ALBERT P. PORR.
